Primary Examiner — T. Chase Nelson*Assistant Examiner* — Ania Aman(74) *Attorney, Agent, or Firm* — Rajesh Vallabh; Foley Hoag LLP(57) **CLAIM**

The ornamental design for umbrella skeleton, as shown and described.

DESCRIPTION

FIG. 1 is a perspective view of umbrella skeleton showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view of a canopy employing the new design;

FIG. 9 is a perspective view of another canopy employing the new design; and,

FIG. 10 is a perspective view of still another canopy employing the new design.

The portions shown in dashed lines do not form part of the design.
